(57) **CLAIM**

The ornamental design for a bird feeder, as shown and described.

DESCRIPTION

FIG. 1 is a first perspective view of a bird feeder showing my new design;

FIG. 2 is a second perspective view thereof;

FIG. 3 is a third perspective view thereof;

FIG. 4 is a front view thereof;

FIG. 5 is a back view thereof;

FIG. 6 is a left side view thereof;

FIG. 7 is a right side view thereof;

FIG. 8 is a top view thereof;

FIG. 9 is a bottom view thereof;

FIG. 10 is a perspective view of another state of the bird feeder thereof; and,

FIG. 11 is an enlarged view of the selected portion 11 in FIG. 1.

The dashed broken lines in the drawings depict portions of the bird feeder that form no part of the claimed design. The dot-dash broken lines in FIGS. 1 and 11 depict the boundaries of the enlargements and form no part of the claimed design.

1 Claim, 11 Drawing Sheets
